MEANS FOR VERIFYING THE CORRECTNESS
OF RECORDING OPERATIONS

Anthony J. Prues, Fort Thomas, Ky.

Application December 26, 1931, Serial No. 583,354

11 Claims. (Cl. 235--23)

My invention relates to means for checking up the operations of persons who are making periodical records, and it is of particular usefulness in determining the accuracy of such operations when performed by persons who are at the same time receiving or disbursing money in a series of individual transactions. My invention will be described in connection with an installation to verify the accuracy of persons who take toll, particularly upon a toll bridge, or the like; but it will be understood, without special description, that my invention is applicable to other situations with or without modification, and that modifications, within the province of those skilled in the art, may be made without departing from the scope of my invention.

In the exemplary installation hereinabove referred to, a toll bridge having a series of different characters of vehicles passing thereover, is equipped with certain collection booths located in positions of convenient access to the various traffic lanes of the bridge. A number of toll gatherers are located in these booths. There is a differential in the toll charged for vehicles of different types, the several tolls however, being related, in this instance, to a series of relatively small whole numbers. As an illustration of the price differential aforesaid, the toll over this bridge for a two or three passenger pleasure automobile is ten cents, whereas the toll for a five passenger pleasure automobile is fifteen cents. Registering mechanisms, conveniently in the form of cash registers, are located in the several booths. The toll gatherer, hereinafter referred to as the operator, accepts from the driver of each vehicle the proper amount of toll, making change as may be necessary; and, depositing this toll in a suitable receptacle, he rings up upon the cash register the amount of toll, which likewise is an indication of the character of the vehicle. The cash registers may be specially built for this use, and will preferably have a series of keys of the particular amounts of the regular tolls. An exemplary type of cash register adapted for this purpose has nine keys, one of them marked special, and the remainder marked in various amounts, ranging from five cents to fifty cents, and progressing from five to thirty cents by intervals of five cents, the remaining two keys being marked respectively forty cents and fifty cents.

The object of my invention, as applied to this situation, is the provision of means for checking up upon the accuracy of the various oper-

ators. Preferably each operator has his own cash register, or where more than one operator is located in a single booth, there may be a cash register having a separate set of keys for each operator, so that the activities of each operator may be separately recorded. It follows, since it is usual for one operator to take the toll of all of the traffic in a single lane, that the cash register record for each operator is supposed not only to represent a full account of that operator's activity during a specified period, but also, in terms of toll rates, a record of the number and character of the vehicles which have passed in that operator's traffic lane.

An object of my invention is to provide means for the discovery of inaccuracy upon the operator's part, either intentional or unintentional, particularly such inaccuracy as results in the making of a false record of the toll amounts gathered. It will be clear that such a false record is likewise a false record of the number and character of vehicles which have passed; and it follows from this that if means are provided for the external checking of the amounts registered against the kind of vehicles passing, inaccuracy can be readily detected. Furthermore, if an external record is kept of the kind of vehicles passing, it will be competent for the management of the bridge to insist that this record correspond to the record made upon the register, and also that the amount of toll turned in by each operator shall be equivalent to the amount of toll indicated by said external record.

To these ends, it is an object of my invention to provide means located at an external point, which means indicate the type of record made by the operator. Said external point will be so located that another person may therefrom observe the character of vehicle passing at the time the record is made. Since said person is concealed from the operator, so that said operator does not know whether he is being checked up on or not, he will be under considerable pressure to make accurate records.

Another object of my invention is to provide means for making a separate record at a remote point, which record must coincide with the record made on the register.

More particularly it is an object of my invention to provide means in connection with the register to indicate at said remote point each individual transaction recorded thereon, which means shall not be liable to falsification at the point where the recording is done.

Consequently a more specific object of my in-

5

50

55

vention is the provision of means which may be attached to a cash register, or the like machine, which means will produce a series of electrical or other impulses representing the record made on the register. It is my object to provide means of this character which are positive in their operation and not liable to be falsified.

In the particular installation referred to, a series of booths are located near one end of the bridge. Substantially abreast of said booths, but to the side of the bridge, there is located a bridge office. A room in said office overlooking the bridge is provided with a shutter, through which a person may observe the traffic passing on the bridge, and means are provided to signal to said person the recording made by the operator. Said person can check visually the accuracy of this recording, so that it is not possible for the operator to record one kind of vehicle as another and 20 keep the difference in toll between the amounts payable upon the said two kinds of vehicles.

These and other objects of my invention which will be set forth hereinafter or will be apparent to one skilled in the art upon reading these 25 specifications, I accomplish by that certain construction and arrangement of parts of which I shall now describe a preferred embodiment, reference being made to the accompanying drawings, wherein:

30 Figure 1 is an elevation of a portion of a cash register with my recording means attached.

Fig. 2 is a plan view thereof, the cover being removed from my signalling mechanism.

35 Fig. 3 is a sectional view of my mechanism with which is combined a circuit diagram and an indication of a recording device.

Fig. 4 is a perspective view of the plunger of my signalling mechanism.

40 Fig. 5 is a partial sectional view of the plunger socket of my signalling mechanism.

Fig. 6 is a perspective view of the plug which is used to mount the plunger in the socket.

One of the problems solved by me is the provision of a convenient, inexpensive but accurate 45 device for attachment to a registering device. It is possible to make a cash register with internal mechanism, whereby the depressing of a key will complete an appropriate electrical circuit. Such registers are, in the first place, somewhat 50 difficult and expensive to construct, and in the second place, are not adapted to the recording of great numbers of transactions. In the particular situation referred to, the number of transactions 55 is so large that the length of life of a cash register is relatively short. Consequently it is not economical to construct a more expensive register having a built-in mechanism for electrical recording; and as a consequence I prefer to provide 60 external electrical signalling means for bodily attachment to a cash register, which means have a great length of life, so that they may be used with succeeding registers, and are also removable for replacement or repair.

65 I have illustrated in Fig. 1 a register having a body 1, which is of semi-circular shape forwardly. From the semi-circular portion of the body a series of the usual keys 2 project. My signalling device is adapted for direct attachment to the 70 body of the register adjacent the line of keys, and has been indicated broadly in Fig. 1 by the numeral 3. It will be clear that my invention is not restricted to use upon registers having semi-circular front portions, and it will likewise be 75 obvious from what follows that the shape of my

signalling device may be varied to cause it to conform and to adapt it to the bodies of registers of different shapes.

As shown in Figs. 2 and 3, my signalling device comprises a base 4, preferably of insulating material, since if so made, special means for insulating the several other parts need not be employed. This plate may be curved, or otherwise formed to fit the face of the register to which it will be applied. To the forward edge of this plate I 10 attach a bar of metal 5, similarly curved. It is my object to clamp between this bar and the base plate 4 a plurality of plunger sockets hereinafter to be described, and which essentially fit in holes indicated at 6 in Fig. 2. In effecting this construction, it is competent to make the bar 5 in the form of a plate and to separate it from the base 4 by means of interspaced plugs of the same or of another material, the spaces between the plugs serving to accommodate the sockets hereinafter to be described; or the member 5 may be in the form of a thick bar or elongated block of metal machined so as to have grooves therein for the reception of said plunger sockets. In Fig. 3 a plunger socket 7 is shown as lying between 15 a portion of the bar 5 and the base plate 4.

The member 5 has, either integral therewith or as a separate piece grazed or otherwise fastened thereto, a rigid member 8, which is drilled and tapped at the proper intervals to receive the set screws 9. These serve to fasten the plunger sockets 7 rigidly in place. The bar 5 may be fastened to the base plate by means of screws or bolts 10, or otherwise, as desired.

35 The plunger mechanisms comprise a socket 7 illustrated in Fig. 5, which socket is conveniently made in the form of a short, rectangular piece of metal having a central circular bore 11. This bore does not extend entirely through the socket, one end thereof being closed by a portion of the metal as at 12, which portion however, is perforated by a rectangular hole 13, through which a portion of the plunger next to be described may slide. The other end of the bore 11 is threaded as at 14 to receive a plug indicated at 15 in Fig. 6. This plug is likewise threaded as at 16, and is provided with a rectangular perforation 17, which, however, is preferably narrower than the perforation 13. A plunger illustrated in Fig. 4 is next provided, and comprises a shank 18, preferably of rectangular shape and terminating in a larger rectangular portion 19. The portion 19 is bifurcated as at 20, and a small roller 21 is pivotally mounted between the bifurcated portions. The dimensions of the shank 18 are such as to permit it to slide freely in the perforation 17 of the plug 15, without, of course, turning therein; and the dimensions of the portion 19 are such as to permit this portion and the roller 21 to slide freely in the perforation 13 of the socket 7.

50 The complete assembly includes also a helical compression spring 22 shown in Fig. 3, of a size to be positioned loosely within the bore 11. One end of this spring, as shown, engages against the plug 15; and the other presses against the plunger itself, engaging the shoulders 19a of the enlarged portion thereof.

55 In assembling this apparatus, it is possible to insert the spring 22 in the bore 11 and then screw in the plug 15, afterward inserting the plunger of Fig. 4, shank end first, through the perforation in the portion 12 of the plunger socket, effecting an assembly as shown in Fig. 3, where the 60

spring 22 in its action opposes movement of the plunger to the right. Obviously the axes of the perforations 13 and 17 will have to lie in the same plane. Stop means may be provided upon 5 the plunger for preventing the withdrawal thereof toward the left, but such means will not ordinarily be required since the contact means hereinafter to be described, and which are subsequently attached to the plunger, serve this function. Shoulders may, however, be formed either 10 upon the portion 19 or the portion 18 of the plunger, and the plunger assembled in the socket by first placing the spring about the plunger shank and the plug 15 thereon, and then while 15 compressing the spring so that the enlarged portion 19 of the plunger lies wholly within the socket, turning the plunger, thereby screwing the plug 15 in place, and finally, when the parts are in alignment, permitting the portion 19 to 20 come out through the perforation 13 in the larger socket.

To my base 4, in a position generally parallel with but interspaced from the bar 15, I prefer to attach a bar of insulating material 23. This 25 may be held in place by screws or bolts 24, or otherwise, and is provided with grooves beneath, indicated at 24 in Fig. 1 for the accommodation of contact members 25. These contact members are conveniently in the form of strips of sheet 30 brass passing beneath the bar 23 and held in clamped position by set screws 26. The contact member has an upturned end 25a upon which I prefer to locate a contact point 27, which may be of some non-oxidizing metal, such as platinum, or any of the suitable contact alloys. 35

A co-operating contact member 28, also preferably of sheet brass, is attached to the end of the plunger shank 18 as shown, and this contact member may likewise have a non-oxidizing contact point 29. The contact points are so located 40 with respect to each other that if the plunger moves to the left, they will eventually come into touching engagement, thereby completing an electric circuit through wires 30, 30a, etc. attached by any suitable means, such as soldering or otherwise, to the contact members 25. A return or ground cable 31 is attached to the bar 5, or the raised member 8 thereon.

To each of the register keys 2, having a shank 50 2a, I attach a cam or wedge member 32. My signaling device is so attached to a register, and the various plunger sockets are so assembled, that one of the rollers 21 lies against the cam 32 of each of the keys 2. I usually prefer to 55 fasten my device to the body of the register by means of suitable bolts, not shown, passing through the base plate 4 thereof. The position of the plunger sockets may be adjusted by means of the set screws 9, and likewise the position of the contact members 25 may be adjusted by means of the set screws 26. It will be clear from Fig. 3 that when the key 2 is not depressed, i. e. when it is in its normal non-registering position, the wedge or cam 32 will hold 60 the plunger, against the force of spring 22, in a position toward the right, whereby the contacts 29 and 27 are separated. If, however, the key 2 be depressed, the roller 21 will ride along the cam or wedge 32, and the plunger will move 65 toward the left under pressure of spring 22 until the contacts 29 and 27 are brought together. At this point, of course, further movement will be prevented and an electrical circuit will be established between the lead or wire 31 and the lead 70 or wire 30, current being conducted through the 75

plunger socket 7 and the plunger itself to the contact arm 28.

I prefer to mount a second bar 33 near the rear edge of my plate, which bar may, if desired, be perforated for the passage of the wires 30, 30a, and etc. More particularly this bar forms a rear closure of my device so that it is possible to place thereon a cover plate 33a, whereby the mechanism is protected from dust, dirt and from unauthorized manipulation.

The cover 33a may be hinged at one end if desired and furnished with a lock 33b. The aspect of the cover as preventing tampering with my apparatus is not particularly important, since although under some circumstances it is possible to send a false signal, this signal can be detected as false either by a visual examination of the vehicle which is passing, or by means of checking the record of the register itself against a record made by my signalling system. So long as the key 2 remains in undepressed position, no contact can be made between the contact points 29 and 27. It is possible to depress a key and fail to send a signal by the act of holding the plunger against movement to the left in Fig. 3, but this not only is difficult in the form of my device, but does not avail the operator anything because of the other features of the check-up system, as will be apparent.

In the check-up room, as aforesaid, I provide 30 a source of power which may be a transformer 34, the primary of which is fed from power leads 35, and the secondary of which feeds main leads 36 and 37. Obviously any other source of power may be employed. In the particular embodiment, I provide not only a switch 38 for the control of power, but also a pilot light 39 connected across the leads 36 and 37 which burns constantly so long as the power is on. The lead 36 is connected to the lead 31, which is the 40 main or ground lead of my signalling apparatus, and the lead 37 is connected to a common lead 40. The several signal leads 30, 30a, and etc. from my signalling device are connected to this common lead 40 through signalling and/or recording means. A convenient signalling means is a lamp 41 which may be arranged to flash behind a stencil or mask indicative of a figure corresponding to the figure on the register key. In commercial operation I prefer to provide in 50 addition to the lamp 41, a lamp 41a connected in parallel therewith, so that the burning out of one lamp will not throw my mechanism out of operation pending a replacement. The lamps 41 and 41a are connected in parallel, and likewise recording means may be connected in parallel therewith, as by leads 42, which leads may go to an electrical counting device of known or commercial form. One such counting device is illustrated in Fig. 3, and indicated broadly by 60 the numeral 43. The same or different counting devices may be attached to each of the several signalling circuits. Instead of counting devices, I may employ a device or series of devices to make any other sort of continuous record.

In the operation of my device, in the particular circumstances of the exemplary embodiment, the operators collecting the toll, register said toll upon the cash registers. My signalling system at the same time effects in the observation room 70 aforesaid an indication of the particular amount rung up on the cash register, which is at the same time an indication of the type of vehicle upon which the toll is collected. An observer in the observation room can see the vehicle as it 75

passes and can verify whether or not the appropriate amount has been rung up, thus preventing intentional fraud or unintentional inaccuracy. In the commercial operation of my device it has not been found possible to operate my signalling system in such a way that it signals the correct amount, although an inaccurate amount is rung up upon the cash register. Even if it were possible to do this, however, the recording apparatus in the observation chamber, keeping a total of the amounts rung up, of various characters, will have to coincide at the end of any given period with the total of the amounts rung up on the cash register, and with the total receipts turned over by the operator. Consequently as respects deliberate fraud, it avails the operator nothing to be able to signal correctly while ringing up incorrect amounts upon the cash register. It will obviously not be necessary for an observer to be at all times stationed in the observation chamber if the object is to prevent deliberate fraud, since the presence or absence of the observer from the observation chamber is not known to the operator who collects the tolls. Consequently, the operator, knowing that he is frequently under observation, and not knowing when he is not under observation, will be under considerable pressure to be accurate in his work.

It will be clear that my invention is not restricted in its utility to the particular exemplary circumstances in connection with which one embodiment of it has been described. It will be useful in a very wide variety of situations where a check-up upon the recording of periodic transactions is desired.

Having thus described my invention, what I claim as new and desire to secure by Letters Patent, is:—

1. In combination with a registering device having movable keys, electric signaling means including spring actuated plungers slidable laterally to the line of movement of the keys and bearing contact members, co-operating contact members, and wedge shaped cams on the shanks of said keys adapted to wedge said contacts into open position when said keys are undepressed.
2. In combination with a registering device, having a plurality of movable keys, electric signaling means including a plate for attachment to said device, a plurality of contact actuating members mounted on said plate and having spring pressed plungers slidable laterally to the line of movement of the keys and bearing contact members, co-operating contact members on said plate, wedge shaped cams on the shanks of said keys for engaging and controlling said plungers and a cover for said plate.
3. In combination with a registering device having depressible keys, a plate for attachment to said registering device, contact actuating members movable laterally to the line of movement of the keys, contacts associated with said plate and wedge shaped cams on said keys, the various parts being so related that said contacts are wedged open by said cams to close when the keys are depressed.

4. In combination with a registering device having movable keys, cams associated with said keys, a plate shaped for attachment to said device, means on said plate for holding contact actuating devices movable laterally to the line of movement of the keys, a plurality of contact actuating devices held by said means and bearing contacts, co-operating contacts mounted on said

plate, and cover means for said plate, said keys having cams so arranged that said contacts may be allowed to close by said cams only upon depressing said keys.

5. In combination with a registering device having movable keys, a plate for external attachment to said device adjacent said keys, clamping means on said plate, a plurality of contact actuating devices held by said clamping means, each of said devices comprising a block having a bore closed at one end, a perforation through said closure, a plunger extending through said perforation movable laterally to the line of movement of the keys, means for closing the other end of said bore and spring means within said bore for actuating said plunger, contact members associated with said plungers and contact members associated with said plate and cam means mounted on said shanks of keys for controlling operation of said plungers.

6. In combination with a registering device having a movable key with a cam, a block having a bore therein closed at one end, a slot through said closed end portion, a threaded plug for the other end of said bore and a slot of less length than said first mentioned slot through said plug, plunger means of bar form having a wide and a narrow portion demarcated by shoulders, said wide and narrow portions being respectively of sizes to pass through said slots, a roller journaled in said wide portion, and spring means for engaging said shoulders and said plug pressing said roller against said cam, a plate, and clamping means on said plate for adjustably holding said contact actuating mechanism, for a desired degree of movement of the plunger relative to the cam.

7. In combination with a registering device having a movable key with a cam, a block having a bore therein closed at one end, a slot through said closed end portion, a threaded plug for the other end of said bore and a slot of less length than said first mentioned slot through said plug, plunger means of bar form having a wide and a narrow portion demarcated by shoulders, said wide and narrow portions being respectively of sizes to pass through said slots, and spring means for engaging said shoulders and said plug, an end of said plunger projecting beyond the end of said block and bearing a roller in contact with said cam, an end of said plunger projecting beyond said plug and bearing a contact member, a plate, clamping means on said plate for adjustably holding said contact actuating mechanism, for a desired degree of movement of the plunger relative to the cam, and a co-operating contact member adjustably associated with said plate.

8. In combination with a registering device having a movable key with a cam, a block having a bore therein closed at one end, a slot through said closed end portion, a threaded plug for the other end of said bore and a slot of less length than said first mentioned slot through said plug, plunger means of bar form having a wide and a narrow portion demarcated by shoulders, said wide and narrow portions being respectively of sizes to pass through said slots, and spring means for engaging said shoulders and said plug, an end of said plunger projecting beyond the end of said block and bearing a roller in contact with said cam, an end of said plunger projecting beyond said plug and bearing a contact member, a plate shaped for attachment to said registering device, means at one edge of said plate for

holding said contact actuating mechanism adjustably, and an interspaced block on said plate for adjustably holding a co-operating contact member.

5. In combination with a registering device having a movable key with a cam, a block having a bore therein closed at one end, a slot through said closed end portion, a threaded plug for the other end of said bore and a slot of less length than said first mentioned slot through said plug, plunger means of bar form having a wide and a narrow portion demarcated by shoulders, said wide and narrow portions being respectively of sizes to pass through 10 said slots, and spring means for engaging said shoulders and said plug, an end of said plunger projecting beyond the end of said block and bearing a roller in contact with said cam, an end of said plunger projecting beyond said plug 15 and bearing a contact member, a plate shaped for attachment to said registering device, means at one edge of said plate for holding said contact actuating mechanism adjustably, an interspaced block on said plate for adjustably holding 20 a co-operating contact member, a block at the opposite edge of said plate adapted to form an edgewise closure, and a cover plate extending 25 between said block and said clamping means.

10. In combination with a registering device 30 having movable keys, cams associated with said

keys, a plate shaped for attachment to said device, means on said plate for holding contact actuating devices, a plurality of contact actuating devices slidable laterally to said keys held by said means and bearing contacts, cooperating contacts mounted on said plate, and cover means for said plate, said elements being so arranged that said cams hold said contacts open, so that said contacts may be closed only upon depressing said keys, electrical circuits associated with said contact actuating means, and a visual indicator at a distance from said registering device actuated by said circuits. 10

11. In combination with a registering device having movable keys, cams associated with said keys, a plate shaped for attachment to said device, means on said plate for holding contact actuating devices, a plurality of contact actuating devices held by said means and bearing contacts, co-operating contacts mounted on said plate, and cover means for said plate, the parts being so arranged that said contacts may be allowed to close only by action of said cams upon depressing said keys, electrical circuits associated with said contact actuating means, and a visual indicator at a distance from said registering device actuated by said circuits, and electrical counting devices also associated with said circuits. 15 20 25

ANTHONY J. PRUES. 30
